(57) **CLAIM**

The ornamental design for an analyser, as shown and described.

DESCRIPTION

FIG. 1 is a front perspective view of the analyser;
FIG. 2 is a rear perspective view of the analyser;
FIG. 3 is a front view of the analyser;
FIG. 4 is a rear view of the analyser;
FIG. 5 is a right view of the analyser;
FIG. 6 is a left view of the analyser;
FIG. 7 is a top plan view of the analyser; and,
FIG. 8 is a bottom plan view of the analyser.
Features shown in dashed lines do not form part of the
claimed design.
